UNITED STATES PATENT OFFICE

132,967

DESIGN FOR A FLOWER HOLDER

Helen M. Twombly, Winchester, Mass.

Application November 18, 1941, Serial No. 104,184

Term of patent 14 years

To all whom it may concern:

Be it known that I, Helen M. Twombly, a citizen of the United States, residing at Winchester, in the county of Middlesex and Commonwealth of Massachusetts, have invented a new, original, and ornamental Design for Flower Holders, of which the following is a specification, reference being had to the accompanying drawing, forming a part thereof.

In the drawing,
Fig. 1 is a perspective view of a flower holder embodying my new design;

Fig. 2 is a plan view of said flower holder;
Fig. 3 is a side elevation of the same.

I claim:

The ornamental design for a flower holder, substantially as shown.

HELEN M. TWOMBLY.
